[57] CLAIM

The ornamental design for an element of a shoe sole, as shown and described.

DESCRIPTION

FIG. 1 is a side elevational view of an element of a shoe sole showing our new design;

FIG. 2 is a side elevational view of the other side thereof; and,

FIG. 3 is a rear view thereof.

The broken line showing of a shoe in FIGS. 1-3 is for illustrative purposes only and forms no part of the claimed design.
